UNITED STATES PATENT OFFICE.

GEORGE W. CLINGAN, OF DAISY, ARKANSAS.

SAFETY-WINDOW FOR CASHIERS' BOOTHS.

1,311,317.

Specification of Letters Patent. Patented July 29, 1919.

Application filed April 12, 1917. Serial No. 161,629.

To all whom it may concern:

Be it known that I, GEORGE W. CLINGAN, a citizen of the United States, residing at Daisy, in the county of Pike and State of Arkansas, have invented certain new and useful Improvements in Safety-Windows for Cashiers' Booths, of which the following is a specification.

My invention relates to safety windows and more particularly to a window for use in bank cashier booths or other places where there are considerable money transactions.

The principal object of the present invention is to provide a safety window which will afford a barricade should any one attempt to hold up the cashier for the purpose of robbery.

It is another object of the present invention to provide a construction of this character which embodies a steel or bullet proof slide and a novel mechanism for holding the slide in raised position which may be easily operated to release the same.

A further object is to provide a construction of this character which is highly efficient and effective and can be conveniently, easily and clearly operated and which will render the occupant of the booth safe against the attack of burglars.

An additional object is to provide a safety window construction of this character which consists of few easily assembled and disassembled parts, can be manufactured and sold to the public cheaply and which consists of few operating parts.

The above and general objects will be fully discussed in the following specification and the inventive features explicitly defined in the appended claims.

The invention is fully illustrated in the accompanying drawings in which—

Figure 1 is a view looking upon the interior of the bank cashier's booth or the like and showing my improved construction, parts of which are in section.

Fig. 2 is an elevation taken at right angles to Fig. 1 and,

Fig. 3 is a detailed view of certain parts used in conjunction with my improved safety window.

In the drawings I have shown a booth consisting of vertical side standards 6 and a transverse bar 7 connecting said side standards at their upper ends. Positioned in the

rear of the booth thus provided and partially supported thereby is the usual counting table 8, above the forward edge of which are arranged grating bars 9 of conventional form.

The inner opposing faces of the standard 6 are grooved longitudinally as indicated at 10, in order to receive the opposite ends of a sliding barricade 11. This barricade 11 is normally supported in an elevated position above the forward edge of the table 8, but in case of attack may be readily released and permitted to descend to a lower position upon the forward edge of the table, in which position, it serves as a shield to protect the occupant of the booth.

To provide for the retention of the barricade in its normal elevated position, the standards 6 are slotted as at 12 and rotatably mounted in these slots by means of pivot pins 13 are the rotatable catches 14. Each of these catches 14 is in the form of a substantially circular disk and has a portion of its periphery cut away to provide a flat face engageable at times with the lower edge of the barricade to retain the latter in its elevated position.

Pivoted and eccentrically secured to each of the catches or disks 14, as at 14', is the upper end of a rod 15. The lower end of these rods are pivotally secured to crank arms 16 formed on the opposite ends of a shaft 17. The shaft 17 is rotatably mounted on the floor within suitable bearings 18 and has its crank arms 16 arranged to operate in slots 19 provided in said floor. The central portion of the shaft is bent to provide a third intermediate crank 19' which is normally engaged by one end of a latch 20 and held in the position shown in Fig. 3. This latch 20 is pivotally supported between a pair of ears 21 and has a coil spring 22 arranged beneath its opposite end. This spring keeps the latch in engagement with the crank 19' and is to be of sufficient strength to prevent rotation of the catches 14 and consequently of the shaft 17 by the weight of the barricade 11.

Mounted above the spring pressed end of the latch 20 is a transversely extending treadle bar 23. This treadle bar has its opposite ends apertured to receive vertical guide pins 24 and embracing each of said guide pins is a coil spring 25 which engages

the under face of the treadle bar to normally retain the same above and out of engagement with the latch.

In practice the barricade 11 is normally retained in elevated position as shown in Fig. 1. The flat faces of the catches 14 are engaged beneath the lower edge of the barricade 11 and are prevented from being rotated to an inoperative position by the weight of said barricade owing to the engagement of the latch 20 with the crank 19. In case of emergency, however, the treadle bar 23 may be depressed to disengage the latch 20 from the intermediate crank 19, thus leaving the shaft 17 free to rotate. The weight of the barricade will then be sufficient to rotate the catches 14 to an inoperative position and the barricade may then descend to its lowermost position.

26. What is claimed is:

1. In a safety window construction, vertical standards having longitudinal grooves therein, a slide mounted in the grooves, pivoted latches for engagement with the slide to retain the same in raised position, rods operatively connected with the latches, a rotatable shaft operatively connected with the rods, a keeper carried by the rotatable shaft, and a latch member adapted for engagement with the keeper to hold the shaft against rotation, the slide being allowed to descend by force of gravity upon the release of the latch from the keeper.

2. In a window construction, vertical standards having longitudinal grooves therein, a slide movable in the grooves rotatable latches pivoted on the standards adapted for engagement with the slide to retain the same in raised position, rods operatively connected with the latches, a rotatable shaft operatively connected with the rods, a keeper carried by the shaft, a latch adapted for engagement with the keeper to hold the shaft against rotation, resilient means urging the latch into such position, and a horizontally disposed bar capable of vertical movement disposed over the last named

latch whereupon depression of the latch the shaft will be free to rotate to allow the slide to descend.

3. In a safety window, a vertically movable slide, latches for retaining the slide in a raised position, rods pivotally connected with the latches, a rotatable shaft operatively connected with the rods, a keeper carried thereby, a latch member adapted for engagement with the keeper to hold the shaft against rotation, vertical stems mounted adjacent the last named latch, a vertical bar slidably mounted on the stems, and expansible means mounted on the stems and urging the bar upwardly.

4. A safety window, including parallel grooved standards having slots communicating with the grooves formed therein, a slide movable in said grooves, rotatable disks mounted in said slot and provided with flattened portion adapted to be engaged beneath said slide to hold the same in an elevated position between said standards, and operating means for rotating said disk out of engagement with said slide to permit downward engagement of the latter between said standards.

5. A safety window, including a vertically movable slide, latches normally retaining said slide in elevated position, a rotatable shaft having cranks formed on its respective ends, an operative connection between said cranks and said latches an intermediate crank formed by said shaft and disposed at an angle to said first mentioned cranks, a latch member normally engaging said intermediate crank to prevent rotation of said shaft, means engageable with said latch to move the same out of engagement with said crank in order to permit rotation of said shaft.

In testimony whereof I affix my signature in presence of two witnesses.

GEORGE W. CLINGAN.
